UNITED STATES PATENT OFFICE.

WILLIAM A. PHILLIPS, OF THE UNITED STATES ARMY.

TYPE-WRITING MACHINE.

SPECIFICATION forming part of Letters Patent No. 498,691, dated May 30, 1893.

Application filed August 25, 1892. Serial No. 444,070. (No model.)

To all whom it may concern:

Be it known that I, WILLIAM A. PHILLIPS, second lieutenant Twenty-second Infantry, United States Army, a citizen of the United States, now stationed at Fort Keogh, in the county of Custer and State of Montana, have invented certain new and useful Improvements in Type-Writing Machines; and I do hereby declare the following to be a full, clear, and exact description of the invention, such as will enable others skilled in the art to which it appertains to make and use the same.

My invention relates to an improvement in typewriting machines, more especially adapted for the Hall typewriter, and it has for its object to promote efficiency and facility of operation of the machine to aid particularly in correcting defective printed or typewritten matter or making a subsequent impression and to these ends the invention consists of the novel construction of certain parts substantially as hereinafter more fully described and pointed out in the claims.

In the accompanying drawings, Figure 1, is a side view of a Hall typewriting machine, with the type-carriage elevated, embodying my improvement. Fig. 2, is a broken plan view of the same, and Figs. 3, 4 and 5, are detailed views and a diagrammatic view thereof.

In carrying out my invention, I employ a preferably V-shaped pointer or index A, having its apex or point adapted to rest upon the paper, used in writing or printing, while its arms or branches a a, at their divergent ends, are extended laterally, one as at a', and the other as at a'', and rest in bearings or brackets b, b', carried by, and connected by screws or otherwise to, the upper end of the type-carriage B, and depending below the same. The laterally extending portion a'', of the index or pointer A, is provided with a handle C, pivoted at a', so as to engage in the notch f, of the bracket b', and against the projection p, of same bracket and by actuating the handle C, the index or pointer can be manipulated so as to cause its point or apex to be raised from the paper and disposed against the under side of the type-carriage B, while said carriage is raised and the paper being taken out or other paper being put in. The V-shaped pointer or index A, is adapted to continually rest above the line of print on the paper to be written or printed upon when

the type carriage is down; but when the type-carriage is raised the index or pointer will be moved along the paper until it points to the exact spot where a letter would be printed if the type-carriage B, were down. Then if the type-carriage is moved laterally while in the raised position it is evident that the pointer or index A, at any time shows the exact spot that a letter would be printed if the type-carriage were to be then stopped and be lowered. It will therefore be seen that, in the event of a defective impression, or failure to print any one or more letters, as not infrequently occurs, by elevating the type-carriage the pointer or index A, so disposes itself that its point or apex rests upon the line on the paper being written upon, and then, by moving the type-carriage so as to align the point of the index with the misprint or space of the omitted letter or letters the desired letter or letters can be produced by lowering the type-carriage to its working position. As the type-carriage is lowered the index or pointer A, automatically moves itself upward still resting on the paper but above the point upon which the latter is to be printed.

The bracket b', is provided with a projection p, against which the side of the handle C, engages when the type-carriage B, is raised to nearly a vertical position. As the carriage is moved upward to rest against the spacing rod, the projection p, raises the handle C, and consequently the pointer or index A, so that said pointer is automatically raised out of the way when the carriage is raised to remove the paper or for any purpose, other than to see the work being done and for corrections. The bracket b', is also provided with a notch f, in which the side of the handle C, can be fastened so as to clamp the index to the under side of the carriage plate. This is done when the machine is not in use in order to prevent the index or pointer from being injured by hanging freely below the position the paper would hold it, if there were any paper in the typewriter. It will be also observed that, with the handle C, of the index or pointer A, raised or brought intermediately of the type-carriage and the index supports as is the case when the index is disposed against the underside of the raised type-carriage the center of gravity of the index or pointer will be brought behind said supports and thus automatically

hold the index out of the way when not in use. When the type-carriage is lowered to be used again the index or pointer A, automatically falls into position on the paper and rests on it all the time while the writing is being done just above the letters being printed so that when the carriage is raised the pivots b' , b , move down and consequently the index moves down to the point the letter is to be next printed if the type-carriage is lowered. When the carriage is lowered the pivots b' , b , move up thus raising the index to its former position resting above the point where each letter is being printed.

15 To put the foregoing in another form, is to state that the index may be raised by the handle C, to such a point that the index by its own weight will rest against the bottom of the type carriage. The projection p of the 20 bracket b , engages the handle C, as the type carriage is revolved about o , see Fig. 5, and raises the index to such a height that it automatically falls against the under side of the type carriage and leans against it as long as 25 it (the type carriage) rests against the scale shaft (Fig. 1). Now, while in this position, it (the index pointer) may be clamped thereby pushing the edge of the handle C, into the notch f (Fig. 4). The index-pointer thus being clamped in position, the type-carriage is lowered and with it the pointer which will drop to the front, and rest upon the paper the handle C, leaving the notch f , and engaging by gravity the projection p , of the bracket 30 b . The point about which the index revolves, revolves in its turn about the same point as the type carriage and with it. And as the type carriage is raised the index is lowered to point to the place where a letter would be 35 printed if the carriage were lowered again.

Referring more especially to Fig. 5, in which the lines represent the different positions of the type carriage and the index as the carriage is raised, the carriage and index, in this 45 instance being designated by the letters O B and a^2 , V, respectively: $o a^2 p P$ is the line drawn through the center o , about which the entire type carriage revolves, and the center a^2 about which the index revolves. $A^2 p$ 50 is the projection p on the bracket b' Fig. 4. $a^2 f$ is the projection f on the bracket b' Fig. 4. C is the handle on $A^2 V$. $g c$ is the vertical line drawn through the center of gravity of $a^2 V$ in the position $o a^2 P V'$. This shows 55 that in the position of $a^2 V$ in its highest position the center of gravity of the index falls behind the point of support a^2 and consequently $A^2 V$ will lean against $o B^2$ in the position $A^2 V^2$. It can be clamped in this position by the handle C being pushed into the notch f of the bracket b' . If the index is not clamped then as the carriage is lowered the center of gravity of $A^2 V$ soon falls to the front of the point a^2 and the index pointer 60 then drops automatically to the front the point V resting on the paper. When O B is first raised to the position O B', a^2 goes up

and just then p' engages C and the point V moves down toward B or the point where the letters are being printed. During the working of the type writer the type carriage is raised only to the position O B', which position puts the point V farthest down toward B.

It will be understood that, although I have described and shown my invention as applicable to the typewriter herein named, it may be employed in connection with various typewriters.

I now claim—

1. In a typewriting machine, the combination, with the type-carriage, of an index or pointer adapted to be extended therefrom and caused to engage the paper being written or printed upon and aligned by the movement of the type-carriage with any letter or space of an omitted letter or letters, when the carriage is raised substantially as set forth.

2. In a typewriter the combination, with the type-carriage, of a V-shaped pointer or index having the divergent ends of its arms or branches hung in brackets or arms depending from the normally upper end of the type carriage, substantially as set forth.

3. In a typewriter the combination with the type-carriage, of a V-shaped index or pointer, having its divergent ends pivoted or hung in brackets or bearings secured to the normally upper end of the type-carriage, and its handle adapted to stand intermediately of the type-carriage and the points of support upon said brackets for said pointer or index, substantially as set forth.

4. In a typewriter the combination with the type-carriage and the V-shaped index or pointer having its divergent ends pivoted or hung in brackets or bearings secured to the normally upper end of the type-carriage, of a bracket provided with a projection which engages the handle standing intermediately of the type-carriage and the points of support, and automatically raises said handle and index when the carriage is raised to its full height, substantially as and for the purposes set forth.

5. In a typewriter the combination with the type-carriage and the V-shaped index or pointer having its divergent ends pivoted or hung in brackets secured to the normally upper end of the type-carriage, of a bracket provided with a notch which is to receive the edge of the handle standing intermediately, the type-carriage and the points of support for the purpose of clamping the said handle and the said index or pointer to the under side of the type-carriage as substantially set forth.

In testimony whereof I affix my signature in presence of two witnesses.

WILLIAM A. PHILLIPS.
